UNITED STATES PATENT OFFICE.

ALFRED L. STREETER, OF CHICAGO, ILLINOIS.

DESIGN FOR A FAN-CASING.

SPECIFICATION forming part of Design No. 35,563, dated January 7, 1902.

Application filed December 11, 1901. Serial No. 85,528. Term of patent 14 years.

To all whom it may concern:

Be it known that I, ALFRED L. STREETER, a citizen of the United States, and a resident of Chicago, in the county of Cook and State of Illinois, have invented and produced a new and original Design for a Fan-Casing, of which the following is a specification.

In the accompanying drawings, Figures 1 and 2 are front and rear views of a fan-casing of my design, and Fig. 3 is a side view thereof.

A fan-casing of my design consists of a base portion 1 and an upward and outward extension 2 on one side of said base portion, which extends downwardly to within a short distance of the bottom of said base portion 1 and upwardly a considerable distance above the same and is relatively thin as compared with said base portion. The sides and top of the base portion 1 are rounded and merge into

each other, so as to form a continuous outwardly convex or rounded surface 3. Adjacent to the bottom of said base portion 1 the side walls thereof extend down on straight lines 4 to form a supporting-surface for said casing. The top 5 and the bottom 6 of the extension 2 are rounded and the lateral sides 7 thereof are straight.

I claim—

The design for a fan-casing substantially as herein shown and described.

In testimony that I claim the foregoing as my invention I affix my signature, in presence of two subscribing witnesses, this 7th day of December, A. D. 1901.

ALFRED L. STREETER.
